UNITED STATES PATENT OFFICE.

JOSEPH H. GLAUBER, OF CLEVELAND, OHIO.

DESIGN FOR A COUPLING-JOINT.

SPECIFICATION forming part of Design No. 33,463, dated October 30, 1900.

Application filed October 4, 1900. Serial No. 32,054. Term of patent 7 years.

To all whom it may concern:

Be it known that I, JOSEPH H. GLAUBER, a citizen of the United States, residing at Cleveland, in the county of Cuyahoga and State of Ohio, have invented and produced a new and original Design for Coupling-Joints, of which the following is a specification, reference being had to the accompanying drawing, forming a part thereof and in which the figure is

5 a perspective elevation of the design.

The essential novelty of my design is comprised in the design as a whole and as it presents itself to the eye, and as thus presented and seen it is found to possess three prominent characteristics by which it can always

5 be recognized and known—viz., a plain cy-

lindrical or tubular form of body *a*, an ornamental head *b*, materially enlarged as respects the outline of the body *a*, and an encircling relief feature *c* about or upon the body, resembling a bead in appearance and having a plain surface with an inward taper or slope noticeable about its upper portion.

What I claim is—

The design for a coupling-joint, substantially as herein shown and described.

Witness my hand to the foregoing specification this 2d day of October, 1900.

JOSEPH H. GLAUBER.

Witnesses:

R. B. MOSER,
M. A. SHEEHAN.
